CONDENSER

Peter G. Jacobson, Chicago, Ill., assignor to Reliance Die & Stamping Co., Chicago, Ill., a corporation of Illinois

Application June 18, 1930, Serial No. 462,036

7 Claims. (Cl. 175—41.5)

This invention relates to certain new and useful improvements in condensers, more especially to condensers of the adjustable type adapted for use in radio apparatus.

5 The invention is here shown as embodied in a condenser comprising a plurality of similar condenser units assembled in a single apparatus for simultaneous adjustment by means of one of the turning dials in a radio set. A single grounded supporting frame supports the various stator elements of the condensers, and a rotary shaft journaled in the frame carries the rotor units or plates of the several condensers.

The principal object of this invention is to provide the improved mechanism for assembling, 15 adjusting and operating the condenser, as disclosed and claimed in the specifications which follow.

Another object is to provide an improved method and means for securing the rotor plates to the rotary shaft.

Another object is to provide an improved means for spacing the rotor plates in properly assembled parallel relation.

25 Another object is to provide improved means for supporting and spacing the stator plates.

Another object is to provide improved means for mounting slip-rings on the rotatable shaft.

Another object is to provide improved means 30 for grounding the rotatable shaft to the frame and for applying an adjustable drag or brake to the shaft.

Another object is to provide an improved "trimmer" or means for making a small fixed adjustment or correction in the capacity of each condenser unit.

Other objects and advantages of this invention will be more apparent from the following detailed description of one approved form of apparatus 40 embodying the principles of this invention.

In the accompanying drawings:

Fig. 1 is a plan view of a portion of the condenser assembly.

Fig. 2 is a side elevation of the structure shown 45 in Fig. 1.

Fig. 3 is a horizontal section taken substantially on the line 3—3 of Fig. 2.

Fig. 4 is a transverse vertical section, taken substantially on the line 4—4 of Fig. 2.

50 Fig. 5 is a transverse vertical section taken substantially on the line 5—5 of Fig. 2.

Fig. 6 is a transverse vertical section taken substantially on the line 6—6 of Fig. 2.

Fig. 7 is a detail longitudinal section taken 55 substantially on the line 7—7 of Fig. 6.

Fig. 8 is a transverse vertical section, taken substantially on the line 8—8 of Fig. 2.

Fig. 9 is a detail longitudinal vertical section 60 taken substantially on the line 9—9 of Fig. 8.

Fig. 10 is a perspective view of a portion of the plate supporting sleeve.

Fig. 11 is a perspective view of one of the rotor plates.

Fig. 12 is a perspective view of one of the stator 65 plates.

The supporting frame is drawn integrally from a single rather heavy sheet of steel or other suitable metal, and comprises a bottom 1, side walls

2, and end walls 3. The end walls 3 extend upwardly at 4 above the side walls 2 and suitable

bearings 5 are mounted in these frame portions

4 in which are journaled the ends of the rotatable

shaft 6. One reduced end portion of shaft 6 is indicated at 7. The other end portion of shaft 6

(not here shown) extends further beyond the

framework and is adapted to be secured to the

actuating dial. The condenser comprises several similar units which are separated by vertical

partitions 8, having projecting tongue portions

9 and 10 anchored in suitable slots or openings in

the framework. The side frame 2 is shown partially

broken away in Fig. 2 to indicate the tongues

10 of partition 9 which engage the bottom 1 of the

frame. The upper portion of each partition 8 is

85 cut away as indicated at 11 (Fig. 6) to provide

ample clearance for the rotatable shaft 6 and the sleeve member carried thereby. An upper ex-

tension 12 of each partition member is secured to

the main lower partition portion 8 by means of

90 downwardly projecting tongues 13 and 14 which

overlap the partition 8 at opposite ends thereof

and are riveted thereto as indicated at 15.

The tubular sleeve 16 which carries the rotor

plates of the condensers is preferably drawn or

rolled from suitable sheet metal, and is adapted

to telescope snugly over the rotatable shaft 6.

The tube 16 is anchored in position on the shaft

6 by means of a pin 17 passed transversely

through the tube and shaft at some suitable point

100 longitudinally thereof. One end of sleeve 16 has

secured thereto a contact plate 18 of brass or

other suitable metal, which forms an outstanding

annular flange adapted to bear against the in-

ner surface of the adjacent end bearing 5. The

105 opposite end of tube or sleeve 16 bears against

the inner surface of the bearing 5 at the other end

of the assembly.

A plurality of separate condenser units are

mounted, one in each compartment of the frame

110 as divided by the partitions 8. In the present ex-

ample, only one end unit and a portion of the

next adjacent unit is shown.

Each condenser unit comprises a plurality

(here shown by way of example as eight) of rotor

condenser plates 19, one of which is shown de-

tached in Fig. 11. Each plate 19 is of generally

semi-circular contour, and is adapted to be at-

tached to the rotatable sleeve at an eccentric or

off-center point on its diametrical side, as usual

115

120

in such structures. A projecting portion 20 has an outer semi-circular contour 21 corresponding to the circumference of tube 16. In this extension 20 is cut a downwardly converging wedge-shaped 5 slot 22, having a central circular enlargement 23 of approximately the same diameter as shaft 6. The outwardly projecting eccentric portion 24 of plate 19 is provided with a short flat side 25 at the end remote from the center of rotation of the 10 plate, from which flat side 25 projects a pair of tongues 26.

The supporting tube or sleeve 16 is provided with a plurality of pairs of opposed slots 27 and 28, spaced at equal intervals longitudinally of the 15 tube. In the present instance there will be eight of these pairs of slots to accommodate the eight rotor plates of each condenser assembly. The two slots 27 and 28 of each pair are positioned in substantially the same plane perpendicular to the 20 axis of the shaft and tube, and each slot is of substantially the same thickness as one of the plates 19. The slots 27 and 28 are cut through the opposite sides of the tubular sleeve but diverge from one another at the same angle as the wedge-shaped recess 22 in plate 19. At the outer divergent ends of the several slots are formed enlarged openings 29, which may be conical or semi-spherical depressions drilled into the outer surface of the tube at the end of each slot. In 25 the process of assembling the plates with the supporting tube, one of the plates 19 is slipped into a pair of slots 27 and 28, from the convergent ends of the slots, the recess 22 being adapted to fit about the portions of the sleeve 16 remaining 30 between the ends of the pair of slots. This assembled position is best shown in Fig. 8. It will be apparent that the enlarged circular portion 23 of recess 22 will now register with the cylindrical passage 30 in tube or sleeve 16, so that the shaft 40 6 may be inserted through the assembled tube and plates. The projecting ends 31 of the extensions 20 of the plates 19 are now peened or upset into the enlarged openings 29 in sleeve 16 so as to rivet the plates in assembled relation with 45 the tube or sleeve. It will be apparent that when the shaft 6 is inserted through the tube the plates will be further locked in position by the engagement of this shaft within the circular openings 23 in the several plates.

50 In order to further hold the group of condenser plates 19 in proper spaced parallel relation, spacer plates 32 provided with openings or apertures formed to receive the tongues 26 are fitted against the flat outer ends 25 of the group of 55 plates, and the outer ends of tongues 26 are then upset or riveted as indicated at 33 so as to lock the spacing plates 32 upon the assembly of rotor plates.

A spring contact member 34 of copper or other 60 suitable metal, is anchored at its lower end 35 in the adjacent end wall 3 of the frame, and the upper forked end 36 of this plate is adapted to bear against the inner surface of annular contact plate 18 on the end of tube 16. A screw 65 37 passes freely through an opening in the end wall 3 and is threaded at its inner end 38 into the spring arm 34. A coiled compression spring 39 is confined around screw 37 between the head 40 of the screw and the adjacent outer surface 70 of end wall 3 of the frame. It will be apparent that the compressed spring 39 will draw the forked upper end 36 of spring arm 34 into clamping engagement with the inner surface of contact plate 18, thus forcing this plate 18 against the adjacent end bearing 5. The force of this

engagement may be adjusted by screwing in or out the adjusting screw 37. This clamping engagement of contact arm 34 against contact ring 18, and of the contact ring against the end bearing 5 serves to exert an adjustable brake or drag 80 on the rotatable assembly, so as to frictionally hold the rotatable parts in any desired position. At the same time this connection serves to properly complete the electrical circuit between the adjacent condenser unit and the framework. 85

Similar electrical connections are provided between each of the other condenser units and the adjacent partitions 8 which separate the frame into the several separate compartments. For this purpose shallow annular channels 41 are formed in tube 16 (one for each condenser unit and adjacent each partition) and in this channel is seated a slip-ring 42, preferably formed of a strip of copper or other suitable metal coiled into the channel. This slip ring 95 is anchored in place by rolling a groove 43 into the metal of the tube 16 adjacent each edge of channel 41, whereby the metal of the tube is rolled over the adjacent edge of the slip-ring 42. All of this is best shown in Fig. 7. A brush- 100 assembly cooperating with this slip-ring comprises a copper plate 44 riveted to the upper partition member at 45, and formed with a pair of downwardly projecting spring contact arms 46 which engage with the opposite sides of slip-ring 42. A projecting arm 47 at the upper end 105 of plate 44 provides for the wiring connection.

Each condenser unit comprises a plurality of stator plates 48 (shown in perspective in Fig. 12), in the present example there being nine of these 110 plates for each condenser unit, the plates being assembled in spaced parallel relation so that the eight plates of the rotor assembly may be inserted in inter-leaved relation with the stator plates, but out of contact therewith. Each stator plate 115 48 is formed in its upper edge with a recess 49 to provide clearance for the rotatable shaft, and is formed with projecting fingers or tongues 50 on its opposite ends. A sheet or block of insulating material 51 is riveted or otherwise secured to 120 one of the side walls 2 of the frame. A metallic supporting bracket 53 is bolted at its upper end as at 54 to the upper portion of insulating plate 51. The inwardly and downwardly projecting portion 55 of supporting plate 53 is formed 125 with a plurality of properly spaced openings to receive the tongues 50 at one end of the group of stator plates 48, these tongues being upset or riveted against the outer surface of plate 53 as indicated at 56.

A second vertically extending plate or block 130 of insulating material 57 is riveted at its lower end as at 58 to the upstanding arm 59 of a right-angled supporting bracket, the horizontal arm 60 of which is secured at 61 to the bottom 1 of the 135 frame. A metallic supporting plate 62 is bolted at 63 to the upper portion of insulating plate 57, this supporting plate 62 being formed with a plurality of spaced openings for receiving the tongues 50 at the adjacent end of the group of stator 140 plates 48, these tongues being riveted in place in the same manner as already described for the tongues at the opposite ends of the plates. Electrical connection with this stator portion of the condenser unit may be made by means of 145 a bracket or contact member 64 held in place by one of the securing bolts 54 (see Fig. 1).

Each condenser unit is provided with a small auxiliary condenser or "trimmer" whereby a fine, fixed adjustment may be made.

A fixed plate 65 is mounted on the upper outer side of insulating plate 57. A thin sheet 66 of mica or other insulating material is held in place by a ring or frame 67, the assembled plates or 5 sheets 65, 66 and 67 being held in place by the bolts 63 already described for holding the supporting plate 62 of the main stator plates. A contact bracket 68 held in place by one of the bolts 63 provides for a separate wiring connection 10 to the stator plate 65. Openings 69 and 70 are made in the supporting plate 62 and stator plate 65 respectively, whereby an outwardly projecting supporting post 71 anchored at 72 in the insulating plate 57 will not have electrical connection 15 with either of these plates. A small movable condenser plate 73 forms the inner flange of a spool 74 slidably supported on the post 71. The post 71 is interiorly threaded to receive a screw 75, the head 76 of which bears against the outer 20 end of spool 74 so as to force the spool inwardly along the post as the screw 75 is advanced into the post. A spring contact arm 77 is anchored at its lower end 78 between the bracket 59 and the lower end of insulating plate 57, and the 25 upper forked end 79 of this spring arm engages the inner flange 80 of spool 74 and tends to force the spool outwardly along the post 71. It will now be apparent that the spring arm 77 will hold the spool against the head 76 of the screw. By 30 merely turning the screw 75, the screw and spring arm will cooperate to minutely adjust the movable contact plate 73 toward or from the fixed contact plate 65. The thin insulating plate 66 prevents direct contact of the two plates 65 and 35 73. After the condenser has been assembled, the several individual condenser units may have their capacities properly balanced by applying a fixed adjustment to each of the several "trimmers" as just described.

40 The several parts described in detail hereinabove comprise, when assembled, a rigid and effective condenser which will not easily get out of proper adjustment, and will be durable and efficient. The several parts of the condenser are 45 economically and quickly stamped and assembled, and no expensive machining operations are required.

I claim:

1. In a condenser, a rotatable shaft, a tubular 50 sleeve adapted to be fitted about a portion of the shaft, there being a plurality of pairs of slots formed at intervals in the sleeve spaced longitudinally thereof, each pair of slots being positioned in the same plane perpendicular to the 55 axis of the shaft and one at either side of the sleeve, the slots intersecting the cylindrical passage through the sleeve, there being enlarged openings formed at one pair of adjacent ends of each pair of slots, and a plurality of condenser 60 plates, each plate being of substantially the same thickness as one of the slots, the plate being formed with a recess shaped to receive the portions of the sleeve remaining between the slots of a pair, this recess having a larger circular central portion to receive the shaft, the free edges of the plate at the open end of the recess being upset into the openings to rivet the plate to the sleeve.

2. In a condenser, a rotatable shaft, a tubular 65 sleeve adapted to be fitted about a portion of the shaft, there being a plurality of pairs of slots formed at intervals in the sleeve spaced longitudinally thereof, each pair of slots being positioned in the same plane perpendicular to the axis of the 70 shaft and one at each side of the sleeve, the slots

intersecting the cylindrical passage in the sleeve and diverging from one another whereby a wider portion of the sleeve remains between one pair of adjacent ends of the slots than remains between the other ends, there being enlarged openings formed in the outer surface of the tube at the divergent ends of the slots, and a plurality of condenser plates, each plate being of substantially the same thickness as one of the slots, the plate being formed with a substantially wedge-shaped recess to receive the portions of the tube remaining between the slots of a pair, the recess having an enlarged circular central portion to receive the shaft, the free edges of the plate at the larger open end of the recess being upset into the 80 openings to rivet the plate to the sleeve.

3. In a condenser, a rotor element comprising a supporting shaft, there being a shallow annular channel formed in the shaft, a split slip-ring of conductive metal fitted in the channel, the edge 85 portions of the shaft at the sides of the channel being rolled in over the edge portions of the slip-ring.

4. In a condenser, a rotor element comprising a supporting shaft, a tubular sleeve fitted about 100 the shaft, a plurality of spaced apart condenser plates secured to the tube, there being a shallow annular channel formed in the tube, a split slip-ring of conductive metal fitted into the channel, the edge portions of the tube at the sides of the channel being rolled in over the edge portions of the 105 slip-ring.

5. In a condenser, a capacity adjustment comprising a fixed condenser plate, a supporting post positioned at right angles to the plate but insulated therefrom, a spool slidably mounted on the post, the inner flange of the spool forming a movable plate member, a spring contact member engaging a portion of the spool remote from the fixed 110 plate and urging the spool away from the fixed plate, and a screw for adjustably forcing the spool toward the fixed plate against the force of the spring.

6. In a condenser, a capacity adjustment comprising a supporting block of insulating material, 115 a fixed condenser plate mounted on the block, said plate having a central aperture therein, a supporting post mounted in the block and projecting centrally through the aperture without electrical contact with the plate, a plate member in the form 120 of a spool slidably mounted on the post, a screw threaded into the end of the post for forcing the spool toward the fixed plate, and a contact member mounted on the insulating block and having a spring portion engaging the spool to urge 125 same away from the fixed plate.

7. In a condenser, a capacity adjustment comprising a supporting block of insulating material, 130 a fixed condenser plate mounted on the block, said plate having a central aperture therein, a supporting post mounted in the block and projecting centrally through the aperture without electrical contact with the plate, a plate member in the form of a spool slidably mounted on the post, a thin sheet of insulating material mounted over 135 the exposed face of the fixed plate to prevent actual contact of the condenser members, a screw threaded into the end of the post for forcing the spool toward the fixed plate, and a contact member mounted on the insulating block and having a spring portion engaging the spool to urge the 140 same away from the fixed plate.
